UNITED STATES PATENT OFFICE.

OTTO NELSON, OF CHICAGO, ILLINOIS.

BOILER FEED.

Application filed November 24, 1919. Serial No. 340,224.

To all whom it may concern:

Be it known that I, Otto NELSON, a citizen of the United States, and a resident of the city of Chicago, county of Cook, and 5 State of Illinois, have invented certain new and useful Improvements in Boiler Feeds, of which the following is a specification.

My invention relates to improvements in boiler feeds, and more especially boiler feeds 10 for ordinary low pressure or heating boilers, the object of the invention being to provide an automatically operating boiler feed by means of which the water level in the boiler will be maintained substantially constant.

15 Other objects will appear hereinafter.

The invention consists in the combinations and arrangements of parts hereinafter described and claimed.

The invention will be best understood by 20 reference to the accompanying drawings forming a part of this specification, and in which—

Fig. 1 is a section taken through the upper 25 end of an ordinary heating boiler equipped with a feed embodying the invention,

Fig. 2 an enlarged vertical section of the feed mechanism,

Fig. 3 an enlarged detailed section of the lower end of a water supply pipe, and

30 Fig. 4 a section taken on line 4—4 of Fig. 2.

The preferred form of construction, as 35 illustrated in the drawings, comprises a float chamber 5 positioned adjacent the side of an ordinary low pressure or heating 40 boiler 6 and extending both above and below the normal water level therein, as shown in Fig. 1. The upper portion of the float chamber 5 is connected by a pipe 7 with the steam space in the boiler 6 and the lower portion thereof connected by a pipe 8 with the water space in the boiler 6, said pipe connections being constantly and entirely open to permit of the rise and fall 45 of the water level in the boiler in the float chamber 5. A water-supply pipe 9 leads downwardly into the top of the float chamber 5, said pipe 9 being connected with the ordinary city water supply system or 50 other source of water under pressure. The lower end of the pipe 9 is provided with a conical valve seat 10 controlled by a conical valve 11 at the upper end of a vertical valve stem 12 projecting upwardly from the top 55 of a float 13 in the chamber 5. A spider 14

is arranged across the lower end of the chamber 5 to limit the downward movement of the float 13 therein, but permitting of the free movement of the water in said chamber. A wire mesh strainer 15 is inserted in the pipe 9 above the valve seat 10 to guard the same against silt, grit, or the like in the water supply.

The arrangement is such that when the water level in the boiler 6 is normal, the 65 float 13 is supported thereby and presses the valve 11 upwardly with sufficient force to close and seal the lower end of the pipe 9, preventing further entry of the water. When the water level of the boiler falls, 70 the float 13 falls with it, thus opening the valve 10—11 and permitting the entry of the water into the boiler. As soon as the normal water level is again reached, however, this water supply is again automatically cut off, thus automatically maintaining 75 the water level, substantially constant.

While I have illustrated and described the preferred form of construction for carrying my invention into effect, this is capable 80 of variation and modification without departing from the spirit of the invention. I, therefore, do not wish to be limited to the precise details of the construction set forth, but desire to avail myself of such 85 variations and modifications as come within the scope of the appended claims.

Having described my invention, what I claim as new and desire to secure by Letters Patent is:

1. A boiler comprising a float chamber positioned adjacent the boiler and extending above and below the water therein; a pipe connecting the upper portion of said chamber with the steam space of said boiler; 95 a pipe connecting the lower portion of said float chamber with the water space in said boiler; a water supply pipe leading into the top of said float chamber and provided with a valve seat above the upper wall of 100 said float chamber controlling the discharge therefrom; a strainer arranged across said water supply pipe above said valve seat; a float in said chamber; a valve stem carried by said float and projecting upwardly therefrom through the upper wall of said float chamber, said upper wall acting as a guide for said valve stem; and a needle valve formed at the top of said valve stem co-operating with said valve seat, whereby 105

the water level in the boiler is maintained substantially constant, substantially as described.

2. A boiler comprising a float chamber positioned adjacent the boiler and extending above and below the water therein; a pipe connecting the upper portion of said float chamber with the steam space of said boiler; a pipe connecting the float chamber with the water space in said boiler; a water supply pipe leading into the top of said float chamber and provided with a valve seat above the upper wall of said float chamber controlling the discharge from said water supply pipe; a float in said chamber; a valve stem carried by said float and pro-

jecting upwardly therefrom through an opening in the upper wall of said float chamber, the sides of said opening serving as a guide for said valve stem; and a conical valve at the top of said valve stem co-operating with said valve seat, whereby the water level in the boiler is maintained constant, substantially as described.

In testimony whereof I have signed my name to this specification in the presence of two subscribing witnesses.

OTTO NELSON.
